UNITED STATES PATENT OFFICE.

JOSEPH HENRY FRYER, OF TORONTO, ONTARIO, CANADA.

FURNACE GRATE.

Application filed April 29, 1926. Serial No. 105,416.

This invention relates to a grate as described in the present specification and illustrated in the accompanying drawings that form part of the same.

5 The invention consists essentially of the novel features pointed out broadly and specifically in the claims for novelty following a description containing an explanation in detail of an acceptable form of the invention.

The objects of the invention are to provide a grate capable of preheating the air forced therethrough and thereby promoting the combustion and eliminating any chance 15 of damage to the grate; to produce a durable, dependable, inexpensive and very efficient grate adapted for the burning of any size or grade of coal, small or large; to supply a grate adapted for burning fuel under natural 20 or forced draft conditions; and generally, to furnish a novel grate, simple in its constructive features and cheap in regard to manufacturing cost, and capable of accomplishing the aforesaid purposes in a very 25 efficient manner.

In the drawings, Figure 1 is a fragmentary perspective view of a furnace, showing the application of the grate.

Figure 2 is a fragmentary plan view of 30 the grate.

Figure 3 is a side sectional view taken along line 1—1 in Figure 2.

Figure 4 is a sectional view taken along line 3—3 in Figure 6.

35 Figure 5 is a top plan view of Figure 6.

Figure 6 is a fragmentary elevation view of the grate member or tuyère.

Figure 7 is a sectional view taken along line 2—2 in Figure 6.

40 Figure 8 is a sectional side view of the grate plates.

Like numerals of reference indicate corresponding parts in the various figures.

In the drawings, 10 is a furnace of conventional design, having the ash door 11 and the lining 12.

13 is the grate, suitably carried or supported by the lining or otherwise, and sealed. An air duct (not shown) is connected 50 to the ash box, for forcing a draft through the grate and fuel bed.

The grate is formed with a number of cast plates 14, having a plurality of spaced countersunk holes 15, in each of which is suspended a ribbed casting, member, or insert 16. The construction of each member,

as will be explained later, is such that it forms with the plate a number of openings or vents 14^A which have the function of tuyères.

60 Casting 16 is formed as shown in Figures 4, 5, 6 and 7, with a flared head 18 and shank 19, and a plurality of longitudinal ribs or ridges 20 forming therebetween the grooves 21. The ribs are of uniform cross-section throughout the length of the shank but gradually change their cross-section from the top of the shank to the top of the head. The ribs on the head gradually increase in 65 width and decrease in height from bottom to top of head, so that the grooves in the head gradually decrease in width and in depth from bottom to top of head, as is clearly shown in Figures 4 and 5. Thus, if a piece of fuel falls through the grate and down a groove, it will fall down into the ash box and will not clog or close the groove, or in other words, will not close the vent 14^A.

70 A casting or member 16 is suspended in each hole, the flared head resting within the countersunk hole; and for purposes of cleaning the grate, the relative size of the head to the hole is made such, that the top surface of the head will lie below the top surface of the grate, leaving a clearance as at 17.

75 When the casting is suspended in its hole, the ribs will bear upon the edges of the hole, and the grooves will form with the plate a number of openings, orifices or tuyères 14^A through which the air can be forced into and 80 through the fuel bed.

85 It will be seen that, since each casting extends below the plate 14 and into the ash box, it will conduct heat from the fuel bed to the ash box where, in radiating, will pre-90 heat the incoming air which is being forced into the fuel bed. And since each casting acts as a conductor of heat, the plate 14 will be kept at a much lower temperature than would be otherwise the case if simply orifices 100 were provided therein.

The orifices also admit the air in a number of jets, and since each jet will be projected into the fuel bed at an angle from the vertical, these jets eventually all meet above 105 the surface of the grate, thus causing between these jets and the plate, a partial vacuum zone. This partial vacuum has the effect of prolonging the life of the plates and of preventing any warping or cracking 110 thereof; and since the fuel or residue thereof rests upon a bed of relatively cooled

metal, fusing of any substance with the grates will be prevented and the residue also easily removable.

It will be noted that if a furnace is to be operated under natural draft conditions, and especially if the mechanical draft suddenly fails, the inserts can be easily removed and the plates 14 will now serve as the grate proper. This grate also allows an even distribution of air pressure throughout the grate since every square inch of the plates becomes effective. By providing a number of grate plates, as shown in Figure 8, contraction and expansion of the grate is easily taken care of.

What I claim is:

1. In a furnace grate, a bed plate having a plurality of spaced holes, and a solid metal insert removably suspended in each of said holes sized to extend below said plate and having a plurality of spaced vertically-arranged ribs in the periphery thereof forming air pre-heating passages to the fire-box of said furnace.

2. In a furnace grate, a bed plate having a plurality of spaced holes, and a solid metal insert removably suspended in each of said holes sized to extend below said grate and formed with laterally extending ribs adapted to pre-heat the air in passage therebetween.

3. In a furnace grate, a bed plate having a plurality of spaced countersunk holes, and a flare-headed solid metal ribbed casting suspended in each of said holes sized to extend below said grate into the ash box of said furnace and having the periphery thereof fluted from top to bottom, said head being sized to allow the top face thereof to lie below the top surface of said plate when said casting is suspended in the plate.

Signed at the city of Toronto, this 3rd day of March, 1926.

JOSEPH HENRY FRYER.
